(57) **CLAIM**

The ornamental design for a convertible spine book, as shown and described.

DESCRIPTION

FIG. 1 is a perspective view of a convertible spine book, showing my design in a first state;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof;

FIG. 7 is a second perspective view of the convertible spine book in a second state;

FIG. 8 is a front elevational view thereof;

FIG. 9 is a rear elevational view thereof;

FIG. 10 is a right side elevational view thereof;

FIG. 11 is a left side elevational view thereof;

FIG. 12 is a top view thereof; and,

FIG. 13 is a plan view of the design in a pre-folded state. The broken lines immediately adjacent the shaded areas represent the bounds of the claimed design while all other broken lines are directed to environment; the broken lines form no part of the claimed design.

1 Claim, 11 Drawing Sheets
